RECORD CHANGING MECHANISM

Russell H. Rich, Elyria, Ohio, assignor to The
General Industries Company, Elyria, Ohio, a
corporation of Ohio

Application April 15, 1938, Serial No. 202,281

8 Claims. (Cl. 274—10)

This invention relates to automatic record changing mechanisms for phonographs of the type adapted to have a plurality of records supported in superposed relation on the turntable, and the records are adapted to be successively played and removed automatically. The invention relates more particularly to improved means for removal of a record at the completion of a record reproduction and re-positioning of the tone arm in a position to initiate reproduction of another record in a phonograph mechanism of the type illustrated in a co-pending application of Paul U. Lannerd, S. N. 75,359, filed April 20, 1936, for Phonograph mechanisms.

15 The aforementioned co-pending application of Paul U. Lannerd discloses an arrangement whereby at the termination of a record reproduction an element is permitted to engage a camming element associated with the drive shaft to effect movement of the element and by suitable link means to concurrently cause a finger to engage and elevate the reproduced record to effect removal of the record from the turntable and to return the tone arm to a position for reproducing the next record. However, the camming arrangement associated with the drive shaft as described in the said co-pending Lannerd application, and in similar types of mechanism, must effect the total movement of the element actuating the linkage in a relatively short interval of time, such as in one-half to two revolutions of the drive shaft. Due to the work required of the drive shaft motor in this short period of time relative to the work required in effecting normal rotation of the turntable, a considerably larger motor is required than under normal operating conditions.

20 I have devised a mechanism which permits the drive shaft to distribute the energy delivered by the motor in effecting removal of a record and re-positioning of the tone arm over a relatively longer period and consequently permits the use of a smaller motor than in prior phonograph mechanisms of this type with which I am familiar.

25 It is an object of my invention, therefore, to provide an improved automatic record removal and reproducing mechanism for phonographs permitting these operations to be effected by a relatively small motor.

30 Another object of my invention is to provide improved automatic record changing and reproducing mechanisms for phonographs wherein the power required to effect these operations is reduced to a minimum through distribution of

the work required over a relatively long interval.

35 Another object of my invention is to provide improved automatic record changing and reproducing mechanisms for phonographs wherein the power required to effect these operations is reduced to a minimum through distribution of the work required over a relatively long interval.

40 Another object of my invention is to provide an improved automatic record changing and reproducing mechanism operable by the drive shaft 10 of a phonograph and wherein the drive shaft goes through several revolutions in effecting these results.

45 Another object of my invention is to provide an improved phonograph mechanism of the above 15 type that is relatively inexpensive to manufacture and operate.

50 Another object of my invention is to provide, in an automatic record changing phonograph, improved positive means to engage the phonograph record changing and tone arm return mechanism with the drive shaft of the phonograph motor.

55 Other objects of my invention and the invention itself will become increasingly apparent 25 from a consideration of the following description of drawings wherein:

Fig. 1 is a top plan view of the main panel of a phonograph mechanism embodying my invention, in which the turntable is removed for clearness and illustrating the position mechanism parts assume during playing of a record;

60 Fig. 2 is a view similar to Fig. 1 illustrating the position of the parts during the discharge of a played record;

65 Fig. 3 is a fragmentary sectional view taken approximately from along line 3—3 of Fig. 2 illustrating the turntable and supported record, together with the turntable driving mechanism;

70 Fig. 4 is a bottom plan view of the mechanism of Fig. 3 taken approximately from plane 4—4 of Fig. 3;

75 Fig. 5 is a view similar to Fig. 4 but showing the mechanism parts engaged with the turntable device shaft;

80 Fig. 6 is a fragmentary sectional view taken approximately from the plane 6—6 of Fig. 2;

85 Fig. 7 is a sectional view of the phonograph mechanism tone arm in stop returned position which it assumes when about to be lowered upon the record, the view being taken at approximately planes 1—7 of Fig. 1 with parts back of the plane omitted for clearness;

90 Fig. 8 is a bottom plan view of a part of the return means illustrated in Fig. 1 and

Fig. 9 is a section taken along line 9—9 of Fig. 1.

Referring now to the drawings, I have shown at 1 a panel preferably formed of sheet metal upon which the principal parts of the phonograph mechanism to be described are mounted on supports, some on the upper side as shown in Figs. 1 and 2, and some on the lower side, as shown in Fig. 3. Panel 1 may be mounted in any desirable cabinet, portable or otherwise, and the reproducing arm generally indicated at 2, may be of the type adapted to energize a remotely disposed amplifier or loud-speaker. On the underside of the turntable 4, as best illustrated in Fig. 3, is mounted a motor 4, adapted to drive a turntable shaft 5, which projects upwardly through a perforation provided in the panel 1, to rotatably drive a turntable 6 upon which may be placed a pile or tier of disc form records 7. In a manner to be described a needle 8, Fig. 9, carried by the reproducing arm 2, engages the record groove of the uppermost record 7 of the tier reproducing the same and at the end of the record reproduction the reproducing arm 2 which may be referred to in some instances as the tone arm, is first elevated from the record towards the starting position and at the same time the finished record is lifted from the pile and is discharged laterally from the pile and the needle 8 is then lowered to engage the next record for initiating the reproduction of the next record. Thus, the entire tier of records may be played, one after the other, automatically.

By means of a lever 9 which may be moved from one position shown in Figs. 1 and 2, to another position, the mechanism may be adapted respectively to reproduce and discharge records of two different sizes, the one change adjustment changing both the record discharge mechanism and the mechanism which positions the tone arm at the beginning of the record. Although for convenience, I have illustrated my improved mechanism to be hereinafter described, as embodying a phonograph adapted to reproduce records of two different sizes, it is understood that it is equally applicable to phonographs adapted to reproduce only a record of a given size and the change adjustment mechanism constitutes no essential part of my invention.

The drive shaft 5 has a portion thereof preferably immediately above the motor housing, formed with axially extending gear teeth to provide a pinion 10 adapted to mesh with a sector gear 11. The tone arm 2 at the beginning of the record occupies the solid line position of Fig. 1 with the needle resting on the record (not shown) and as the motor drives the turntable and the uppermost record therewith, the needle follows the spiral groove of the record and the arm 2 is slowly propelled clockwise until the needle reaches the terminal groove of the record. Such terminal grooves, as is well known, may be slightly eccentric and in which case the tone arm will be oscillated in the terminal position or the terminal groove may be spiraled, in which case the tone arm in the terminal position may be given a quick clockwise movement.

The tone arm 2 as best illustrated in Figs. 6 and 7, carries thereon a three-prong device generally indicated at 12, one prong of which has a tooth 13 projecting therefrom. As tone arm 2 reaches the end of the record, of the type which oscillates the arm, the tooth 13 will ride up on a ratchet plate 15 mounted on an arm 16, pivoted at 17 on the panel 1, and will by engage-

ment with teeth on the ratchet plate 15, move the arm 16 counter clock-wise as viewed in Fig. 1. If the terminal groove is of the spiral type, another depending prong 14 will engage an up-standing post 18 on the arm 16 and move the arm counter-clockwise as viewed in Fig. 1. The end of the arm 16 remote from the pivot 17 has a V-form cam notch 19 therein which engages a pin 20 on the arm 21 pivoted on the panel 1 by a screw 22 which permits arm 21 to oscillate horizontally and vertically. Movement of the arm 16 in either direction therefor, at the end of a record reproduction will cause the cam notch 19 to act on the pin 20, to move the arm 21 clockwise, as viewed in Figs. 1 and 2.

A spring 23 acts to constantly and yieldably hold the arm 21 in the counter-clockwise direction with the pin 20 against the cam notch 19 so as to always return it thereinto, but allow it to ride therefrom. Rocking the arm 21 clockwise as described, removes a hook portion 24, formed thereon, Figs. 1 and 2, from engagement with a post 25, projecting upwardly from a lever 26 which is pivoted on panel 1 as indicated at 27 to oscillate horizontally. The lever 26 has an arm 28 projecting laterally therefrom and a spring 29 constantly urges the arm 28 and lever 26 to rotate counter-clockwise on the pivot 27 so that when the post 25 is released from the hook portion 24, the arm 26 moves counter-clockwise under the impulsion of the spring 29 and the end 30 thereof is thereby moved from the position illustrated in Fig. 1 towards the left to engage the drive shaft in a manner to be described. The manner of effecting movement of arm 26 in a counter-clockwise direction at the end of a record reproduction so that the inner end of arm 26 approaches the drive shaft constitutes no essential part of my invention, and any suitable arrangement other than that shown may be employed.

The mechanism for operably linking lever 26 with the drive shaft to effect rotation of lever 26 in a counter-clockwise direction as viewed in Fig. 1, will now be described. As previously mentioned, the lever 26 is pivoted to the panel at 27 as indicated in Fig. 3 through a bolt 100 which is projected through a perforation in lever 26, through a washer 101, and through a perforation in the panel 1 to form a pivotal mounting for a lever 102. This mounting is preferably effected by a spacing collar 103 and a washer and lock nut as indicated at 104. The panel 1 is provided with an arcuate slot 105 having a center of radius coinciding with the pivotal axis of the levers 26 and 102, the levers being inter-connected to concurrently move about said axis by means of a bolt 106 projected through a perforation in lever 26 and threadingly engaging lever 102. The levers are maintained in parallel-spaced relation through the provision of a spacing sleeve 107.

The lever 102 which is disposed beneath the panel 1 supports an arm 108 which is integral with sector gear 11. The arm 108 is provided with a longitudinally extending slot as indicated at 109 and pins 102a having head portions greater than the width of the slot 109 are projected through slot 109 and secured in any suitable manner to lever 102 as by flanging the pins 102a. Thus, the arm 108 and its associated sector gear 11 are permitted to move longitudinally relative to the supporting lever 102.

An arm 110 is pivoted to panel 1 laterally of lever 102 as indicated at 110a, Fig. 1, and the opposite end of arm 110 is provided with a pin 111

which projects into slot 109 of sector gear arm 108, whereby when the sector gear arm is rotated with the supporting lever 102, the pin 111 will be constrained to move longitudinally relative to lever 102. Also, the arm 108 and sector gear 11 may move longitudinally relative to lever 102 independently of movement of pin 111. Sector gear arm 108 has two depending pins affixed thereto as indicated at 112 and 113, and each of said pins are connected with pin 111 by means of tension springs indicated at 114 and 115 whereby movement of pin 111 along slot 109 from a predetermined position, will place one of said springs under tension tending to return arm 108 and its associated sector gear to a given position.

The pin 113 has a portion projecting upwardly from arm 108 as indicated at 116 which is adapted to engage an arcuate flange 117 of an angle element 118 arced about the pivotal axis 27 of the levers 26 and 102 as a center of radius. In the position illustrated in Fig. 3 the pin portion 116 engages the forward face of arcuate flange 117 and the sector gear is maintained in engagement with the pinion portion 10 of the drive shaft 5.

As best illustrated in Fig. 4 an arm 119 is pivotally supported on the underside of the sector gear 11 as indicated at 120, one end of the arm 119 being provided with a plurality of gear teeth aligned with and forming a continuation of the gear teeth on the sector gear and adapted to engage the teeth of the pinion portion 10 of the drive shaft in a manner and for a purpose to be described. The opposite end of arm 119 is provided with a pin 121 to which is secured one end of a tension spring 122, the opposite end of spring 122 being secured to a pin 123 fixed to the sector gear whereby the toothed end of arm 119 will be continuously urged in a direction to engage the pinion portion of the drive shaft 5. A second pin 124 fixed to the sector gear limits movement of the toothed portion of arm 119 towards the pinion 10—but does not prevent movement in a reverse direction against the tension of spring 122.

The manner of operably moving lever 26 about its pivotal axis 27 through power imparted from the drive shaft and the linkage mechanism, as above described, will now be described. During playing of a record the arm 26, as best illustrated in Fig. 1, will be maintained in the full line position shown and upon completion of the record the end 30 of arm 26 will be permitted in a manner previously described, to move counter-clockwise and will carry its associated lever 102 aligned therewith beneath the plate 1 also counter-clockwise. During playing of a record the sector gear is in the position illustrated in Fig. 1 wherein the pin 111 has assumed a position increasing the tension on spring 114 and diminishing the tension of spring 115 and the spring 114 acting on pin 112 urges the arm 108 of sector gear forwardly in the general direction of the drive shaft 5 so that the pin portion 116 fixed to the sector gear will engage the forward face of arcuate flange 117 as the lever 102 and arm 108 move in a counter-clockwise direction as illustrated in Fig. 1. In order to provide a sliding engagement of pin portion 116 with flange 117, the end of flange 117 is beveled as indicated at 117a. When the end 30 of arm 26 is permitted to move counter-clockwise, the arm 119 mounted on the sector gear moves towards the drive shaft, and the teeth of arm 119 resiliently engage the pinion 10 of drive shaft 5

and as the pinion revolves the teeth of the sector gear mesh therewith. The pin portion 116 through engagement with the forward face of arcuate flange 117 maintains the sector gear in engagement with pinion 10 of the drive shaft 5 so that the sector gear and its associated parts are revolved counter-clockwise until the pin portion 116 is carried beyond the flange 117 and since during this movement pin 111 increases the tension on spring 115 the sector gear and arm 108 are drawn rearwardly so that pin portion 116 is in a position to engage the rearward face of arcuate flange 117. The parts of the mechanism described are preferably so designed that the rearward movement of sector gear 11 occurs slightly subsequent to the disengagement of the sector gear and the pinion 10 of the drive shaft.

Any suitable means may be employed for returning the levers 26 and 102 together with associated parts to the position illustrated in Fig. 1 or a position to again effect re-positioning of the tone arm and removal of the record but I preferably employ an arrangement best indicated in Figs. 6 and 8. The arm 26 has a pin 130 secured thereto and which projects downwardly through a generally square perforation provided in panel 1. The pin 130 is adapted to engage an arm 131 pivoted on the under side of panel, as indicated at 132 and which is additionally supported by a screw 133 engaging the arm and projected through an arcuate slot provided in a plate 134 whereby the arm 131 may be permitted to move freely. The arm 131 will be moved in a clockwise direction as viewed in Fig. 8 during engagement of the sector gear with the pinion portion of the drive shaft 5 and this movement will exert tension on a spring 135 secured to the arm 131 and panel 1. Thus, the spring tension will always tend to return the arm 26 to the position illustrated in Fig. 1 and this will be effected when the sector gear is pulled rearwardly out of engagement with the pinion 10 of the drive shaft permitting this return movement. The arcuate slot 105 in panel 1 limits the return movement 45 and the equalizing tension of the springs 114 and 115 associated with lever 102 effect a braking action as the return position is approached. Thus, I have described an arrangement whereby the lever 26 at the completion of a record reproduction may be automatically rotated by the drive shaft a pre-determined amount and placed in a position to again be actuated by the drive shaft at the completion of the playing of another record. 55

It will be noted that the construction described due to the number of teeth on the sector gear and the arm 119 relative to the number of teeth on the pinion 10 of the drive shaft, permits several revolutions of the drive shaft to be effected 60 while in engagement with the sector gear so that the work done in moving lever 26 and associated parts may be distributed over a relatively long time interval requiring a small power motor as compared to a construction wherein this work 65 must be effected in from one-half to two revolutions of the drive shaft. It will be apparent that the number of teeth in the sector gear may be increased if desired but I have found that the ratio indicated will operate satisfactorily so that 70 the power required in removing a record and re-positioning the tone arm is not substantially in excess of that required to drive the turntable during the playing of a record.

The manner in which the aforementioned 75

- movement of lever 26 effects repositioning of the tone arm will be briefly described and a more detailed description may be found in the aforementioned co-pending application of Paul U. 5 Lannerd, S. N. 732,248, filed June 25, 1934, for Phonograph record changing mechanism. As best illustrated in Figs. 6 and 7, the tone arm 2 is mounted to oscillate both in a horizontal and vertical direction and the prong tooth 13 associated with the tone arm is provided with a roller 35 disposed above the arm 21 whereby lifting of one end of the arm 21 will lift the tone arm from the terminal groove of the record to cause the tone arm to move by gravity with the 15 aid of roller 35 about a pivotal support toward a support device to be later described. To elevate one end of arm 21 the lever which is positioned beneath the arm 21, is provided with a roller 33 engageable with a depending cam portion 31 of arm 21 and as lever 26 is moved horizontally to the left as viewed in Fig. 6, the cam portion is caused to ride on roller 33 and elevate arm 21. 20
- As best illustrated in Fig. 9, the tone arm is provided with a bracket 51 and a laterally extending wing 53 whereby the tone arm will be engaged by a stop post generally indicated at 63 through the bracket 51 acting as a stop means and the wing 53 overlapping the upper end of the post to support the tone arm thereon. The 25 stop post is so adjusted that the arm is supported in a position above a record whereby lowering of the arm will insert the needle 8 in a peripheral groove of the record to initiate reproduction of the record. The stop post in a 30 manner more fully described in the said co-pending Lannerd application is adapted to lower the tone arm on to the record and then return to operative position to again receive the tone arm. Although any suitable means may be employed 35 for lowering the tone arm on to the record, I preferably employ a dash-pot arrangement whereby the weight of the tone arm transmitted to the stop post through engagement with a frusto-conical cup 75 effects downward movement of the cup and an associated weight 70 until the 40 tone arm is supported on the record. To elevate the weight 70 and the cup 75, I preferably provide a hanger 81 secured to arm 21 and projecting downwardly through a suitable perforation 45 on panel 1 to engage a bar 78 pivotally supported on the underside of the panel and having a finger 83 adapted to engage the weight 70 and elevate it and also cup 75 as the arm 21 is raised through movement of lever 26.
- 50 The mechanism for removing the record will now be briefly described and a more detailed description of this mechanism may be found in the aforementioned co-pending Lannerd application. The arm 28 which is attached to lever 26 acts through a link 85 and a crank 86 to rotate a post 87 upon which is vertically oscillatably mounted a record pick up arm 88. The pick up arm is adapted to be elevated through a finger 88a thereon engaging an upstanding post 90. 55
- 60 When the pick up arm is rotated with the post from the position of Fig. 1 to that of Fig. 2, the end of the pick up arm will engage the edge of the topmost record and the rotation of the underlying records will cause the topmost record 65 to be moved laterally from the pile. When the lever 26 has moved counter-clockwise as viewed in Fig. 1, a pre-determined amount, it will be permitted to move in a reverse or clockwise direction, and this movement is aided by a spring 70 75 84 secured to panel 1 and also to lever 28 and

which is placed under tension as the lever 26 moves counterclockwise. Movement of lever 26 in a clockwise direction returns arm 28 and through the link means described, the pick up arm 88 to the position illustrated in Fig. 1.

Thus, I have provided a relatively simple arrangement for re-positioning the tone arm to play another record upon removal of the topmost record from the pile on the turntable and also for removing the topmost record concurrently with re-positioning of the tone arm. The positive drive engagement with the drive shaft assures that these operations will always be properly effected and at the same time the drive shaft goes through several revolutions in effecting these results and a sudden increase in driving power for a short interval is eliminated permitting a relatively small motor to be employed since the power required to effect these operations is not substantially in excess of that required for normally driving the turntable and supported records.

Although I have shown and described a preferred embodiment of my invention, I contemplate that numerous and extensive departures may be made therefrom and that my invention is equally applicable to a mechanism for playing different sized records or the same sized records and irrespective of the type of adjustment if the phonograph mechanism is adapted to different sized records.

Having thus described my invention, what I claim is:

1. In a phonograph mechanism of the type comprising a record discharge mechanism and a tone arm positioning mechanism, means for effecting the operation of the record discharge mechanism including a movable element, a pinion on the drive shaft of the phonograph mechanism, a sector gear movable longitudinally of the movable element, linkage between said movable element and said discharge mechanism, means for maintaining the sector gear in an engageable path but out of connection with the pinion during playing of a record, means causing the sector gear to move along said path in the completion of a record reproduction to engage the pinion to actuate the movable element, means for moving the sector gear to a disengaged path after the movable element has been actuated a predetermined amount, and means for reversing the movement of the movable element to the initial position.

2. In a phonograph mechanism of the type comprising a record discharge mechanism and a tone arm positioning mechanism, a movable element operably connected with the record discharge mechanism and tone arm positioning mechanism, a pinion integral with the phonograph mechanism drive shaft, a sector gear associated with the movable element and movable longitudinally therealong, means for moving the sector gear along the movable element into engagement with the drive shaft pinion at the completion of a record reproduction, means maintaining said sector gear in engagement with the pinion to effect a predetermined movement of the movable element, means for withdrawing the sector gear along the movable element at the completion of said movement, and spring means returning the sector gear to a position to again engage the pinion.

3. In a phonograph mechanism of the type comprising a record discharge mechanism and a tone arm positioning mechanism, means for

operating said discharge mechanism including a movable element operably connected to the record discharge mechanism and the tone arm positioning mechanism, a pinion integral with the phonograph mechanism drive shaft, a sector gear associated with the movable element, the sector gear being movable longitudinally of the movable element, spring means for moving the sector gear along the movable element into engagement with the drive shaft pinion at the completion of a record reproduction, means maintaining said sector gear in engagement with the pinion to effect a predetermined movement of the movable element, means for withdrawing the sector gear along the movable element at the completion of said movement, spring means returning the sector gear to a position to again engage the pinion, and means maintaining the sector gear in the withdrawn position during said return movement.

4. In a phonograph mechanism of the type comprising a record discharge mechanism and a tone arm positioning mechanism, a movable element mounted to pivot in a substantially horizontal plane and operably connected to the record discharge mechanism and tone arm positioning mechanism, a pinion integral with the phonograph mechanism drive shaft, a gear associated with the movable element and movable longitudinally relative thereto, means positioning the gear adjacent the pinion and in a path to engage said pinion during the playing of a record, means for moving the gear into engagement with the pinion, means withdrawing the gear from engagement with the pinion after the element has been rotated a predetermined amount, means maintaining the gear in the withdrawn position, and means returning the movable element and the gear to the initial pinion engageable path.

5. In a phonograph mechanism of the type comprising a record discharge mechanism and a tone arm positioning mechanism, means for effecting the operation of the record discharge mechanism including a movable element, a pinion on the drive shaft of the phonograph mechanism, a sector gear movable longitudinally of the movable element, linkage between said movable element and said discharge mechanism, means for maintaining the sector gear in an engageable path but out of connection with the pinion during playing of a record, means causing the sector gear to move along said path in the completion of a record reproduction to engage the pinion to actuate the movable element, means for moving the sector gear to a disengaged path after the movable element has been actuated a predetermined amount, means for reversing the movement of the movable element to the initial position, and supplementary means carried by said sector gear comprising a plurality of sector gear teeth disposed in substantial alignment with the teeth of said sector gear and positioned laterally outwardly therefrom, forming additional teeth for said sector gear, said supplementary means also comprising a portion for supporting the teeth thereof in proper aligned position with the teeth of said sector gear, and spring means for yieldingly opposing displacement of said supplementary means from said aligned position, the teeth of said supplementary means adapted to make initial meshing engagement between said pinion and said gear sector.

6. In a phonograph mechanism of the type comprising a record discharge mechanism and a tone arm positioning mechanism, a movable element operably connected with the record discharge mechanism and tone arm positioning

mechanism, a pinion integral with the phonograph mechanism drive shaft, a sector gear associated with the movable element and movable longitudinally therealong, means for moving the sector gear along the movable element into engagement with the drive shaft pinion at the completion of a record reproduction, means maintaining said sector gear in engagement with the pinion to effect a predetermined movement of the movable element, means for withdrawing the sector gear along the movable element at the completion of said movement, and spring means returning the sector gear to a position to again engage the pinion, and supplementary means carried by said sector gear comprising a plurality of sector gear teeth disposed in substantial alignment with the teeth of said sector gear and positioned laterally outwardly therefrom, forming additional teeth for said sector gear, said supplementary means also comprising a portion for supporting the teeth thereof in proper aligned position with the teeth of said sector gear, and spring means for yieldingly opposing displacement of said supplementary means from said aligned position, the teeth of said supplementary means adapted to make initial meshing engagement between said pinion and said gear sector.

7. In a phonograph mechanism of the type comprising a record discharge mechanism and a tone arm positioning mechanism, means for operating said discharge mechanism including a movable element operably connected to the record discharge mechanism and the tone arm positioning mechanism, a pinion integral with the phonograph mechanism drive shaft, a sector gear associated with the movable element, the sector gear being movable longitudinally of the movable element, spring means for moving the sector gear along the movable element into engagement with the drive shaft pinion at the completion of a record reproduction, means maintaining said sector gear in engagement with the pinion to effect a predetermined movement of the movable element, means for withdrawing the sector gear along the movable element at the completion of said movement, spring means returning the sector gear to a position to again engage the pinion, means maintaining the sector gear in the withdrawn position during said return movement, and supplementary means carried by said sector gear comprising a plurality of sector gear teeth disposed in substantial alignment with the teeth of said sector gear and positioned laterally outwardly therefrom, forming additional teeth for said sector gear, said supplementary means also comprising a portion for supporting the teeth thereof in proper aligned position with the teeth of said sector gear, and spring means for yieldingly opposing displacement of said supplementary means from said aligned position, the teeth of said supplementary means adapted to make initial meshing engagement between said pinion and said gear sector.

8. In a phonograph mechanism of the type comprising a record discharge mechanism and a tone arm positioning mechanism, a movable element mounted to pivot in a substantially horizontal plane and operably connected to the record discharge mechanism and tone arm positioning mechanism, a pinion integral with the phonograph mechanism drive shaft, a gear associated with the movable element and movable longitudinally relative thereto, means positioning the gear adjacent the pinion and in a path to engage said pinion during the playing of a record, means

- for moving the gear into engagement with the pinion after the element has been rotated a predetermined amount, means maintaining the gear in the withdrawn position, means returning the movable element and the gear to the initial pinion engageable path, and supplementary means carried by said sector gear comprising a plurality of sector gear teeth disposed in substantial alignment with the teeth of said sector gear and positioned laterally outwardly therefrom, forming

additional teeth for said sector gear, said supplementary means also comprising a portion for supporting the teeth thereof in proper aligned position with the teeth of said sector gear, and spring means for yieldingly opposing displacement of said supplementary means from said aligned position, the teeth of said supplementary means adapted to make initial meshing engagement between said pinion and said gear sector.

RUSSELL H. RICH.
